UNITED STATES PATENT OFFICE.

HARRY W. HILL, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

LENS-BLOCKING MACHINE.

1,415,560.

Specification of Letters Patent.

Patented May 9, 1922.

Application filed January 18, 1919. Serial No. 271,874.

To all whom it may concern:

Be it known that I, HARRY W. HILL, a citizen of the United States, residing at Southbridge, in the county of Worcester 5 and State of Massachusetts, have invented certain new and useful Improvements in Lens-Blocking Machines, of which the following is a specification.

This invention relates to new and useful 10 improvements in blocking machines, and more particularly to lens-blocking machines. The main object of the present invention is the provision of a machine of the above character whereby the lens blanks are correctly positioned within the grinding lap 15 prior to their insertion within the grinding machine.

Another object of the present invention is to provide a lens-blocking machine whereby 20 the lens will be blocked upon the block and inclined to a tilting position with respect to the block on which the lens is to be attached.

It is well known in the art of grinding 25 lenses that the lens blank is first attached to what is known as a block, said lens being attached thereto through the medium of pitch, Canadian balsam, or any similar adhesive, prior to the grinding operation, and one of 30 the main objects of this invention is the provision of a machine particularly adapted for positioning upon the block what is known in the art as bifocal lenses. Lenses being blocked by this machine are positioned within 35 the block in a tilted position to correspond with the grinding tool of the grinding machine whereby the segments of the lenses will be disposed in their correct positions before the grinding operation is carried out. 40 With the above and other objects in view, the invention consists in the novel features of construction and the combination and arrangement of parts hereinafter more fully set forth, pointed out in the claims and 45 shown in the accompanying drawings, in which—

Figure I is a side elevation of a blocking machine constructed in accordance with my invention, parts thereof being broken away 50 and illustrated in cross section.

Figure II is a front elevation.

Figure III is a transverse sectional view taken on the line III—III of Figure I.

In the general construction of my improved

machine I provide a base member 1 having attached thereto the upright standard 2 and a block 3 to which is attached an upright socket 4 adapted to receive the stem 5 of the lens block 6. In the present instance the block 6 has been shown of the concave type and having attached thereto a lens 7, but it will be understood that different forms of blocks may be used in connection with the machine. The standard 2 is provided with a curved arm 8 at the upper end thereof, at the outer end of which is formed a sleeve 9 through which operates a vertical shaft 10.

Extending at right angles to the standard 2 at a point adjacent the upper end thereof is a guide arm 11 having formed at its outer end a sleeve 12 adapted to be arranged in longitudinal alinement with the sleeve 9 whereby to receive the lower end of the shaft 10. This sleeve 12, as illustrated, is of the split type and provided upon one side thereof with the ears 13 securely clamped together by means of the bolt 14.

The shaft 10 which is reciprocated through the guide sleeves 9 and 12 is provided at its lower end with a blocking member 15 of a circumferential type which is formed with a receiving pocket 16 upon its lower face adapted to receive the head 17 of the plunger 18. This plunger 18 is mounted for reciprocating movement within the socket 19 formed within the lower end of the shaft 10. In order that the head 17 may be normally disposed in position in advance of the head 15 I provide a coil spring 20 which is disposed between the inner end of the socket 19 and the plunger 18 whereby to normally retain the plunger in a projected position. The plunger is provided with a longitudinal slot 21 preferably arranged at the central portion of the plunger and adapted to receive a cross pin 22 carried by the shaft 10 whereby to limit the reciprocating movement of the plunger.

In order to provide means for imparting a reciprocating movement to the shaft 10 the standard 2 is first provided with an enlarged portion 23 having formed therein a transverse opening 24 through which extends a shaft 25, said shaft extending transversely through the standard and out through the bearing sleeve 26, and having attached to its outer end an operating lever 27. Mounted upon the shaft 25 and hav-

ing its inner end disposed within the opening 24 is an arm 28 which extends outwardly toward the shaft 10 and is provided at its outer end with parallel arranged spaced arms 29 adapted to be disposed upon opposite sides of the shaft 10 and provided with slots 30 to receive the projecting ends of the pin 22 whereby to loosely connect the shaft 10 with these arms 29 whereby upon rotation of the shaft 25 the arm 28 will be raised and lowered and thus impart movement to the shaft 10 through the medium of the arms 29.

In order to normally retain the shaft 10 in a raised position I provide a coil spring 31, the upper end of which is attached to a perforated ear 32 formed on the arm 8, while the other end extends down through an opening 33 in the arm 11 and is attached to a cross pin 34 which extends between the two arms 29. From this it will be apparent that when the lever 27 is operated to reciprocate the shaft 10 in a downward movement, the spring 31 will be placed under tension so that when the lever is released, the tension of the spring will return the shaft 10 to its normal raised position.

Particular attention is hereby called to the fact that the lower faces of the block 15 and head 17 are slightly inclined so that when they contact with the lens 7 the lens will be moved to an inclined position with respect to the block 6. In the operation of my improved blocking machine the block 6 is first placed in position beneath the reciprocating shaft 10 and a coat of pitch or other adhesive applied to the upper face thereof. The lens 7 is then placed upon the upper face of the block and the shaft 10 reciprocated by means of the lever 27 so as to bring the head 17 into contact with the upper face of the lens which will tend to hold the lens in position until the block 15 is brought into contact with the same whereby further pressure of the block through the medium of the lever 27 will tend to securely press the lens 7 into position upon the face of the block 6, and as the lower faces of the block 15 and head 17 are slightly inclined the lens 7 will be slightly tilted or disposed at an inclined position with respect to the block. After the lens has been properly positioned within the block 6 the hand lever 27 is released and the coil spring 31 returns the shaft 10 to its normally arranged position while the plunger head 17 will be projected again through the medium of the coil spring 20. From the above description taken in connection with the accompanying drawings it will be readily apparent that I have provided a lens-blocking machine whereby the lenses of the bifocal type are correctly positioned within the grinding lap before be-

ing placed in the grinding machine, and by having the blocking tools provided with inclined faces, it will tend to position the lenses within the lap so as to bring them into correct grinding position with respect to the grinding tool.

I claim:

1. A lens blocking machine including a frame, a movable shaft carried thereby, a blocking member carried by the shaft, a plunger mounted for reciprocating movement within the shaft, a head carried by said plunger and normally disposed in advance of the blocking member, means to support a lens block in opposition to the shaft and means for imparting a reciprocating movement to said shaft and plunger, as and for the purpose set forth.

2. A lens blocking machine including a vertical movable shaft, a blocking member carried thereby, a plunger mounted for reciprocating movement within the shaft, a head carried by the plunger and normally disposed in advance of the blocking member, a coil spring arranged within the shaft and disposed between the end of the plunger and a portion of the shaft to normally retain said plunger in an advanced position, and means for imparting a reciprocating movement to the shaft and plunger, as and for the purpose set forth.

3. A lens blocking machine including a vertical reciprocating shaft having a central bore, a blocking member carried by the shaft having a tapering lower face, a plunger mounted within the bore of the shaft, a head carried by the plunger and normally disposed in advance of the blocking member, said head being provided with an inclined lower face corresponding with the lower face of the blocking member, yielding means disposed within the bore of the shaft and bearing against the end of the plunger for normally retaining the head in advanced position, and means for imparting a reciprocating movement to said shaft and plunger, as and for the purpose set forth.

4. A lens blocking device including a lens block support, and a plunger in alignment therewith, said plunger having a head for engagement with the lens formed with its contacting face disposed at an oblique angle to the direction of reciprocation of the plunger for tiltingly blocking a lens, substantially as and for the purpose described.

5. A lens blocking machine including a frame, a reciprocating shaft carried thereby, a blocking member at one end of the shaft, a reciprocating plunger carried by the shaft, a head on the lower end of the plunger, a transverse shaft carried by the frame, means forming a connection between the transverse shaft and the vertical shaft and plunger, and means for actuating the transverse shaft to impart a downward movement to the

shaft and plunger, and additional means for returning the shaft and plunger to their normal raised position upon release of the actuating means.

- 5 6. A lens blocking machine including a frame and reciprocating shaft carried thereby, a blocking member at the lower end of the shaft, said shaft having a central bore therein, a reciprocating plunger mounted 10 within the bore, a head carried by the plunger and normally disposed in advance of the blocking member, a transverse pin extending through the shaft and plunger and the plunger having a slot in which the pin operates, 15 and means connected with the pin whereby downward movement may be imparted to the shaft and plunger, and additional means

for returning the shaft and plunger to their normal raised position.

7. A lens blocking machine including a lens block support, a lens steadyng member for holding a lens in position on the block, and a lens pressing member having its contacting portion angularly disposed with respect to the block to press the lens into tilted 25 relation to the block, substantially as and for the purpose described.

In testimony whereof I have affixed my signature, in presence of two witnesses.

HARRY W. HILL.
